UNITED STATES PATENT OFFICE.

JOSEPH VIOZZI, OF HAMILTON, ONTARIO, CANADA.

MECHANICAL HORSE.

Application filed December 12, 1921. Serial No. 521,819.

To all whom it may concern:

Be it known that JOSEPH Viozzi, a subject of the King of Italy, residing at Hamilton, in the county of Wentworth, and

5 Province of Ontario, Canada, has invented certain new and useful Improvements in a Mechanical Horse, of which the following is a specification.

10 My invention relates to improvements in toy vehicles representing mounts such as horses for example, that may be mechanically propelled along the ground by the rider, and consists essentially of an image mounted on two rear wheels and one forward wheel, a drive pulley connected by a suitable belt to a pulley on the rear axle, stirrups connected to crank hangers co-operating with the drive pulley, steering column and novel means for guiding the vehicle by 15 right and left pull upon reins.

20 The object of the invention is to provide a vehicle of the class specified which affords the maximum of reality to the juvenile rider, inasmuch that the rider's feet occupy 25 genuine stirrups which are used as a means for actuating the propulsion mechanism, and that the vehicle is guided by mechanism designed to outwardly appear to be 30 reins and bit.

30 A further object is to provide such a vehicle which will be simple, durable, efficient, and comparatively inexpensive to manufacture.

35 With these and other objects in view the invention consists in the construction, combination, and arrangement of the parts as will be hereinafter more fully described, illustrated in the accompanying drawing, and pointed out in the claim hereunto appended.

40 Referring to the drawing:

Figure 1 is a side elevation of the invention;

45 Figure 2 is a rear elevation thereof;

Figure 3 is an enlarged detail side view of the image;

Figure 4 is an enlarged detailed top view of the steering column and forward wheel;

50 Figure 5 is a side view of that shown in Figure 4;

Figure 6 is an enlarged edge view of a fragment of the driving belt;

Figure 7 is an enlarged face view of the belt;

55 Figure 8 is an enlarged detailed top view of the drive pulley; and,

Figure 9 is an enlarged sectional side view thereof taken on the line 9-9 in Figure 8.

Similar reference characters refer to 60 similar parts throughout the several views.

Within the body portion of the image is a flanged drive pulley 2 rigid on the horizontal shaft 3 having bearing in journals 4, and rigid on the ends of said shaft are crank 65 hangers 5 extending in opposite directions to each other. A pair of stirrups 6 are secured to flexible straps 7 which are pivotally connected to the free ends of said crank hangers and depend therefrom by gravitational force.

Journalized horizontally in the rear hoofs of the image is an axle shaft 8 having rigid on its end parts ground wheels 9, and provided intermediately of the legs of the 75 image with a flanged pulley 10.

This latter pulley is connected to the pulley 2 by a belt 11 which is deflected by deflector sheaves 12 journaled in the body of the image, in order to conceal as much as 80 possible of it within the body. The belt 11 is provided with a plurality of equally spaced studs 13 which engage correspondingly spaced pockets 13 in both pulleys in order that the belt shall not slip or slide 85 thereover. The vehicle is propelled by rotating the pulley 2 with the feet positioned in the stirrups 6.

The steering column 15 is rotatably sleeved in the neck of the image, and is provided 90 with a rigid T-head 16 to the ends of which cables 17 are connected. These cables pass through a passage way provided in the top of the neck and which continues through the lower part of the head, from whence they 95 pass around grooved idler sheaves 18 rotatable on a rigid shaft 19 secured in the jaws of the image. The free ends of said cables are secured to reins 20 by which the steering column 15 may be rotated in either 100 direction by corresponding pull on the reins. The lower end part of the steering column is provided with a rigid bifurcated member 21 in which a ground wheel 22 is journalled.

Having now fully described my invention, what I claim and desire to secure by Letters Patent, is:-

In an apparatus of the class described, the combination with an image of a mount, an axle journaled in the rear hoofs of the 110 image, ground wheels on said axle, a flanged pulley rigid on said axle, a drive pulley

2
journalled in the body of the image, crank
hangers co-operating with the drive pulley,
stirrups pivotally suspended from the free
ends of said crank hangers, a belt connect-
ing said pulleys, a plurality of equi-
distantly spaced studs on said belt engag-
ing correspondingly spaced pockets in said
flange pulley and drive pulley, a steering
column rotatably sleeved in the neck of the
image, a forward ground wheel connected
10 to the steering column, a T-head on the up-

per end of said column, sheaves journaled in
the mouth of the image, cables secured to
the free ends of said T-head and passing
around said sheaves, and reins connected to 15
the free ends of said cables.

In testimony whereof I have affixed my
signature.

JOSEPH VIOZZI.
